Inventor:

Albert L. Nickerson
by his atty. *Charles S. Gooding*

UNITED STATES PATENT OFFICE.

ALBERT L. NICKERSON, OF BROCKTON, MASSACHUSETTS.

CONTAINER.

Application filed July 3, 1920. Serial No. 393,879.

To all whom it may concern:

Be it known that I, ALBERT L. NICKERSON, a citizen of the United States, residing at Brockton, in the county of Plymouth and 5 State of Massachusetts, have invented new and useful Improvements in Containers, of which the following is a specification.

This invention relates to containers of the class known as collapsible tubes and more 10 particularly to a cap for said container and means for securing said cap to said container.

The object of the invention is to provide a simple, inexpensive cap for a container, 15 the said cap being so constructed and attached to the neck of the container that it may be quickly and easily moved into closed or opened position without accidentally becoming detached from said container and 20 lost.

The invention consists in the combination and arrangement of parts set forth in the following specification and particularly pointed out in the claim thereof.

25 Referring to the drawings:

Figure 1 represents a front elevation of a container embodying my invention.

Fig. 2 is an elevation as viewed from the right of Fig. 1.

30 Fig. 3 is a longitudinal section taken on the line 3—3, Figure 2.

Fig. 4 is an elevation similar to Figure 1 illustrating the cap in its uppermost position.

35 Fig. 5 is an elevation similar to Figure 4 illustrating the cap in a position to allow the contents of the container to be removed therefrom.

Fig. 6 is a plan view of Figure 4.

40 Fig. 7 is a plan view of Figure 5.

Like numerals refer to like parts throughout the several views of the drawings.

In the drawings, 1 represents the main body portion of a container preferably a 45 collapsible tube formed of soft metal, although it should be understood that my invention is capable of being embodied in other types of containers where a suitable neck portion is provided. 2 represents the

50 neck portion of the container, the said neck portion having grooves 3 upon opposite sides thereof, a portion 4 of said grooves extending longitudinally of the neck portion and each terminating at their lower ends in 55 a helical portion 5 which extends a portion

of the distance around the circumference of the neck. The upper end of the longitudinal portion 4 of the groove 3 terminates a short distance below the upper end of the neck and the end of said groove constitutes a stop 60 to prevent the removal of a cap 6 from said neck. A passage 7 extends through the neck portion 2 connecting with the interior of the container, the said cap 6 being provided for the purpose of closing said passage.

The cap 6 is constructed to closely fit the neck portion 2 and is provided with two ears 8 upon opposite sides thereof, the said ears each having a projection 9 extending inwardly therefrom and formed integral 70 therewith adapted to project into the grooves 3. It is evident that in place of forming the projections 9 integral with the ears 8 that pins may be provided secured to the said ears without departing from the 75 spirit of this invention. The lower edge of the cap 6 is so cut away at 10 that when the projections 9 are located at the upper ends of the longitudinal portions 4 of the grooves 3 as illustrated in Figure 4, that the cap 6 80 may pivot in the upper ends of said grooves and swing to the position illustrated in Figures 5 and 7, at which time the passage 7 is entirely opened and the contents of the container may be removed therefrom in the 85 usual well known manner without danger of losing the cap or without the said cap interfering with the removal of the said contents from the container.

In closing the container the cap is moved 90 to the position illustrated in Figure 4 and then pushed downwardly until the projections 9 reach the bottom of the longitudinal portion 4 of the grooves 3 and the cap is 95 then rotated whereupon the projections 9 will engage the upper edges of the helical portions 5 of the grooves 3 thereby forcing the under surface of the cap 6 tightly against the top of the neck of the container as illustrated in Figures 1, 2 and 3 thereby 100 tightly closing the passage 7.

Having thus described my invention what I claim and desire by Letters Patent to secure is:

A container having, in combination, a 105 neck portion provided with grooves formed in the opposite sides thereof and closed at their upper ends said grooves each comprising a portion extending longitudinally of said neck portion and a helical portion ex- 110

tending circumferentially around said neck portion, a cap slidably mounted upon said neck portion and embodying therein ears having projections thereon adapted to engage the helical portion of said grooves whereby said cap may be forced against the upper end of said neck portion, said projections also constituting pivots for said cap when said projections are located at the

upper ends of the longitudinal portion of 10 said grooves.

In testimony whereof I have hereunto set my hand in presence of two subscribing witnesses.

ALBERT L. NICKERSON.
